UNITED STATES PATENT OFFICE.

CHARLES J. COOK, OF ST. PAUL, MINNESOTA.

EXTENSION-TABLE.

SPECIFICATION forming part of Letters Patent No. 723,140, dated March 17, 1903.

Application filed April 26, 1902. Serial No. 104,902. (No model.)

To all whom it may concern:

Be it known that I, CHARLES J. COOK, a citizen of the United States, residing at St. Paul, in the county of Ramsey and State of Minnesota, have invented certain new and useful Improvements in Extension-Tables; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in extension-tables; and the main object of the invention is to provide an extension-table in which all the leaves may at all times be conveniently contained in the table, whether the table be more or less extended or not extended at all. This object I attain by the novel construction and arrangement of parts illustrated in the accompanying drawings, in which—

Figure 1 is a top or plan view of my improved table in the closed position. Fig. 2 is a side elevation of Fig. 1. Fig. 3 is a top view of the table fully extended. Fig. 4 is a side view of Fig. 3 without legs. Fig. 5 is an enlarged cross-section on the line *a* *a* in Fig. 4 looking into the central section of the table. The loose leaves 23 and 15 are, however, in this view shown in folded position, as when pushed into the central section of the table, and the links and bars supporting the loose leaves are shown both in raised and lowered position. Fig. 6 is an enlarged bottom view of the table with the legs in section near the table and one end section pushed into the central section of the table.

Referring to the drawings by reference-numerals, 1 designates the central section of the table. This section consists of a fixed leaf and a frame composed of the side pieces 2 and cross-bars 3, secured to the lower edges thereof. To said cross-bars 3 are secured by screws 4 the strips 5, to which are again secured the legs 6, either one leg to each end, as in lower strip, or one leg in the middle, as in upper strip in Fig. 6. Into the space thus formed between the cross-bars 3 and the central leaf of the table I insert the end leaves, as will presently be fully described.

The table may be considered as consisting of a central section with a fixed leaf 1 and two slidable frame-sections 7 and 8, supported by the legs 9. The frame-section 7 is formed with a pair of slidable bars 10, which are grooved sidewise to fit the dovetailed side rib 11 of the longitudinal guide-bars 12, fixed upon the cross-bars 3 of the central frame. At the opposite sides of the bars 12 slide likewise a pair of horizontal bars 13, projecting from the frame-section 8. Said end sections of the frame carry each a fixed portion 14 of the table proper, which are always at a level with the central fixed leaf 1.

The slidable frame-section 8 carries a series of narrow loose leaves 15, 15^a, and 15^b, each of which are secured on two bottom cleats 16, pivotally connected each by a pair of links 17 to the sliding bars 13, so that the top of the table may be gradually diminished by folding the links of one or more leaves 15, 15^a, and 15^b toward the central section of the table, so that the links assume the horizontal position and the leaves 15 rest upon the bar 13 and slide into the central section, resting also upon the top of the bars 12. In order to thus insert the small leaves 15 into the central section, the end pieces 15^d of the small leaves are secured to the leaves by hinges 18, which may be of metal or of suitable strong canvas, so that the ends may be folded, as in Figs. 5 and 6, in which position they are held by the ledges 19 of the central frame until pulled out and elevated by raising the links, after which the table is pushed together, so that the dowel-pins 20 engage and hold the end pieces in horizontal plane. The other end frame 7 also has a few links 21, pivoted to the sliding bars 10 and supporting two link-bars 22, on the top of which rest loosely the large loose leaf 23, which has also end pieces 23^a hinged to it at 24 and adapted to fold in under the leaf and be held folded by the ledges 25, as shown in Fig. 5, until put in use by being elevated on the link-bars 22 and engaged by the dowel-pins 26.

From one link of each of the bars 22 projects downwardly an arm 27. These arms are secured together by a rod 28, from which extends about horizontally a longitudinal rod 29, guided in a vertically-slotted guide or staple 30 and provided at its under side with

a ratchet-tooth 31, which when the bars 10 are pulled to their limit out of the central section engages the guide or staple 30, and thereby causes all the links 21 to rise from 5 a horizontal to a vertical position, thereby bringing the link-bars 22 and the leaf 23 to full elevation by simply pulling the end section of the table out. When this is done, the end section is pushed back sufficiently to 10 make the leaf 23 fit properly between the leaves 1 and 14. When the leaf 23 is to be lowered and pushed into the central section, the operator pulls the end section outward about an inch, or so that the leaf 23 is set 15 free from the dowel-pins. He then puts his hand under the end of the table, lifts the rod 29 so that the tooth 31 clears the bottom of the staple 30, and pulls the rod outward so that the links fall horizontal, with the tops of 20 the link-bars flush with the tops of the bars 10 and 12, so that the small leaves 15 may pass over the link-bars. The leaf 23 is then moved so that it rests on the blocks 32, projecting upwardly from the adjacent ends of 25 the frame-bars 12. The leaf also rests on two blocks 33, projecting out of the frame-section 7 and having each a dowel-pin 34, engaging a hole or indenture 35 in the under side of the leaf, so as to hold the leaf in place on said 30 supporting-blocks while the end section is pushed into and pulled out of the central section.

36 in Fig. 6 represents stops to prevent the link-bars 22 from falling below the horizontal 35 position, and 37 represents collars to prevent sliding of the rod 29 on the rod 28.

38 represents pins secured in the sliding bars 10 and 13, adapted to engage the terminus 39 of the grooves 40 in the cross frame- 40 bars to limit the extension of the table. 41 represents grooves clear across said frame-

bars to permit said pins to pass over the bars 3 which they are not to engage.

In a cheap grade of the table the rod 29 and staple 30 may be dispensed with, as the bar 45 or rod 28 may be operated by the hand in both directions. Such and similar modifications I do not mean or wish to confine my invention to.

Having thus described my invention, what 50 I claim, and desire to secure by Letters Patent, is—

1. In an extension-table the combination with the central section 1 and its frame, of the guide or staple 30 at its bottom, the sliding section 7 having the loose leaf 23, the link-bar 22 and links 21 supporting same; two of said links having the arms 27 secured together by the rod 28 the rod 29, inserted in the staple and provided with the tooth 31 and 60 being connected to the rod 28, substantially as and for the purpose set forth.

2. The combination with the central table-section having a fixed leaf and the fixed guide-bars 12, of the sliding end section 8 65 having a series of leaves adapted to be lowered and pushed into the central section below the fixed leaf, the sliding end section 7, having the single leaf 23 adapted to be pushed into the central section between the fixed leaf 7c and the series of leaves of the opposite end section, the short blocks 32 secured upon the ends of the bars 12, and the blocks 33 having the pins 34, and indentures in the leaf 23 for said pins to engage in and move the leaf, substantially as and for the purpose set forth.

In testimony whereof I affix my signature in presence of two witnesses.

CHARLES J. COOK.
